United States Patent Office

Des. 188,196
Patented June 14, 1960

188,196

BUFFET

John J. Lubberts and Lambert J. Mulder, Grand Rapids,
Mich., assignors to Thomasville Chair Company,
Thomasville, N.C., a corporation of North Carolina

Filed May 20, 1959, Ser. No. 55,997

Term of patent 14 years

(Cl. D33—6)

Fig. 1.

Fig. 2.

Des. 188,196

Fig. 3.

Fig. 4.

The back is plain and unornamented.

We claim:

The ornamental design for buffet, substantially as shown, and described.
